F. J. GARRETY

DISPLAY SAMPLE DEVICE

Filed Oct. 19, 1926

Inventor

Frank J. Garrety,

By Murray & Gegelet

Attorneys.

UNITED STATES PATENT OFFICE.

FRANK J. GARRETY, OF CINCINNATI, OHIO.

DISPLAY SAMPLE DEVICE.

Application filed October 19, 1926. Serial No. 142,744.

This invention relates to a device for use by salesmen and the like in selling made-to-order clothing, and has for an object the provision of a device wherewith the salesman may give a prospective customer a definite visual exhibition of the appearance of the cloth as it will appear, or make up in the garments.

Another object is to provide a device for the purpose stated which is especially adapted to an effective display of cloth which is to be used in men's made-to-order clothing, comprising coats, trousers and the like.

Another object is to provide a device for the purpose stated which may be used to show the finished edge on the bottom of coat sleeves or trouser legs, with and without cuffs.

Another object is to provide a device of the class described which is effective in showing the nature of the goods, especially as to its tendency to hold creases, wrinkle and other desirable characteristics of woolens, suitings, and the like, and to enable prospective customers to note the absence of undesirable characteristics in such samples.

These and other objects are attained by the means described herein, and disclosed in the accompanying drawing, in which:

Figure I, is a fragmental perspective view, showing the lower limb and foot of a person, and having the display sample of my invention in an operative position for showing the effect and appearance of a given sample of goods, as relates to trousers having cuff bottoms.

Figure II, is a perspective view of the same sample showing its position when used to simulate cuffless trouser legs.

Figure III, is a fragmental perspective view of a man's coat with a sample of my invention displayed upon the arm to show the appearance of a coat sleeve.

Figure IV, is a plan view of the sample of my invention, with corner thereof upturned.

Figure V, is an enlarged fragmental view taken on line 5—5 of Figure IV.

In showing cloth, such as woolens, suitings, and the like to a customer, it is always advantageous to be able to permit the customer to visualize as nearly as possible the appearance of the suit or garment which is to be made from the cloth. The merchant tailor who carries bolts of goods in his stock,

usually drapes a portion of the material over the person of a prospective customer for this purpose. A salesman, however, who calls upon customers and prospects, in an endeavor to sell them a suit of clothes, must rely upon samples. These samples, are usually made as small as possible in order to economize upon the cloth used for the purpose, and are very ineffective, because the customer not only fails to visualize the appearance of a whole garment, but often fails to properly visualize those portions of a garment which are of extreme importance to its total finished effect.

The sample of my invention is provided by cutting a rectangular section from a bolt of goods, and having the longitudinal edges, 8, pinked. One of the remaining edges, 9, is turned under and secured by blind stitching, 10, or the like, while the opposite end, 11, is turned under for a relatively longer distance and also secured by suitable blind stitching, 10, after which, the resultant relatively deep hem is folded upon the top of the cloth, creased, and tacked to simulate trouser cuffs of approved or fashionable width. The sample of cloth, 7, is then folded double, pressed and creased at 12, whereupon, it is ready for use by the salesman.

The method of using the sample will be readily apparent from Figures I, II, and III. It will be readily understood that when a customer desires to know whether a pair of trousers made of a given sample of goods would become him, or suit his fancy, the sample would be spread out and draped over the lower, front trouser leg for attaining an actual visual effect of a given pattern of goods. If the prospect is undecided as to whether trousers should have cuffs, or be cuffless, the folded or plain end of the sample would be accordingly placed toward the foot. Inasmuch as the appearance of the sleeve of a coat is usually amply indicative of the appearance of the garment, the sample is draped over the arm of the customer, with the cuffless end toward the hand, or in some instances where a cuff may be desired on the sleeve, the turned up end of the sample is disposed toward the hand.

The tendency of the goods to hold creases may be readily established to the satisfaction of the customer, by permitting him to handle and crush the sample in his hand, and to afterwards observe the condition of the sam-

ple. By providing a sample which is somewhat longer than the normal fore-arm of an adult, the general appearance of patterned goods may be established in the mind of the most unimaginative prospective customer.

From the foregoing, it will be apparent that there has been provided a novel and useful sample device, which, while especially useful to salesman who carry their samples about with them, is very useful to the woolen merchant or the merchant tailor who serves his customers at the place where the bolts of goods are available.

15 5 What I claim is:—

1. As a new article of manufacture, a piece of sample cloth for displaying the effect of the cloth in the form of a finished garment, comprising an elongated strip of cloth, folded and creased substantially at the center thereof, having a hem at its one end, and a turned over fold at its opposite end.

20 2. In a piece of sample cloth, the combination of an elongated strip of cloth provided with a longitudinal crease, a turned under end, and a turned up opposite end.

25 3. As a new article of manufacture, a piece of sample cloth comprising an elongated strip of cloth, longitudinally creased, and having its one end turned under and

the opposite end folded up to effect the appearance of a trouser cuff.

4. As a new article of manufacture, a longitudinal strip of sample cloth, having pinked longitudinal edges, a turned under lateral edge, and an upwardly folded opposite lateral edge, said strip being longitudinally folded and creased.

5. As a new article of manufacture a piece of sample cloth comprising a longitudinally creased elongated strip of cloth.

6. As a new article of manufacture a piece of sample cloth having a preformed crease pressed therein.

7. As a new article of manufacture a piece of sample cloth having a longitudinal crease and having its ends extending transversely to the crease finished to simulate garment edges.

8. As a new article of manufacture, a display piece of sample cloth comprising a longitudinally creased strip of cloth having a hem at one end and a cuff at the opposite end, said sample being adapted to be draped over the person for producing the visual effect of a hemmed garment or a cuffed garment.

In testimony whereof, I have hereunto subscribed my name this 5th day of October, 1926.

FRANK J. GARRETY.
